The ornamental design for a toaster having adjustable openings, as shown and described.

DESCRIPTION

FIG. 1 is a perspective view of the toaster having adjustable openings embodying the design of the present invention;

FIG. 2 is a front elevational view thereof, the rear being a mirror image of the front shown in FIG. 2;

FIG. 3 is a left end elevational view thereof;

FIG. 4 is a right end elevational view thereof;

FIG. 5 is a top plan view thereof; and,

FIG. 6 is a bottom view thereof.

The electric power cord is shown in FIGS. 1, 2, 5 and 6 in cutoff fashion for simplicity of disclosure.

FIG. 1

FIG. 2
